UNITED STATES PATENT OFFICE.

RAY JENNINGS, OF LA GRANGE, MISSOURI.

CUP.

1,380,481.

Specification of Letters Patent. Patented June 7, 1921.

Application filed March 11, 1921. Serial No. 451,472.

To all whom it may concern:

Be it known that I, RAY JENNINGS, a citizen of the United States, and a resident of the city of La Grange, in the county of 5 Lewis and State of Missouri, have invented a new and useful Improvement in Cups, of which the following is a full, clear, and exact description.

My invention relates to improvements in 10 cups and it consists in the combinations, constructions, and arrangements herein described and claimed.

An object of my invention is to provide a 15 device of the character described that is adapted to hold a liquid so that a person may drink therefrom while in a reclining or recumbent position without inconvenience or discomfort and without spilling the liquid.

20 A further object of my invention is to provide a device of the character described that has means operable to prevent the flow of a liquid therefrom.

25 A further object of my invention is to provide a device of the character described that is simple in construction and operation, and thoroughly effective for the purpose intended.

30 A further object of my invention is to provide a device of the character described that is capable of being manufactured cheaply and is otherwise practical commercially.

35 Other objects and advantages will appear in the following specification, and the novel features of the invention will be particularly pointed out in the appended claims.

40 My invention is illustrated in the accompanying drawings, forming part of this application, in which,

Figure 1 is a side elevation of a portion of the device,

Fig. 2 is a similar view of another portion of the device, and

Fig. 3 is a central longitudinal section through the device.

45 In carrying out my invention, I provide a receptacle or liquid container comprising a lower member 1, that is preferably made of glass and has the form of an ordinary glass tumbler, and an upper member 2, that is preferably made of a light metal, such as aluminum, and is preferably threaded externally at one open end thereof for engagement with the threaded open end por-

tion of the lower member 1 until the open upper end of the latter abuts a transverse partition 3 that is firmly secured within the upper member 2 considerably nearer 60 to the lower end thereof than to its upper end, which is also open, as shown. In the present instance, I have shown both the lower member 1 and the upper member 2 as being cylindrical although obviously they 65 may be polygonal, elliptical, or other shape in section, since it is only essential that the upper member fit the lower member tightly so that liquid will not pass between the 70 contiguous walls of the two members and so that the two members will not be likely to be disengaged accidentally.

The partition 3 is formed with an opening 4 therethrough adjacent its edge and for this opening a closure 5 is provided. 75 The latter is hinged at 6 to the upper side of the partition 3 and is normally maintained in closed position by the action of a compression spring 7 that has one end secured to the upper side of the partition 80 3 so that the other end thereof reacts against an arm 8 having one end secured to the closure 5 at the point of its hinged connection with the partition 3 so that movement of the arm 8 swings the closure 5 about the 85 pintle of its hinge.

The arm 8 is connected at its other end by a link 9 with one end of a bell crank lever 10 that is fulcrumed at 11 on the inner wall of the upper member 2. The bell 90 crank lever 10 carries at its free end a push button 12 that projects through an opening 13 in the wall of the upper member 2 externally of the latter.

From the foregoing description of the 95 various parts of the device, the operation thereof may be readily understood. An apparent utility of the device is in a sick room where the patient is confined to bed. The liquid to be drunk is placed within the 100 tumbler 1 and the upper member 2 is fitted thereon. The closure 5 is normally maintained in closed position and the push button 12 is likewise normally maintained in extended position by the action of the compression spring 7. The push button 12 is moved inwardly by the pressure of a thumb or finger and the closure 5 will be opened so that liquid may flow from the tumbler 1 into the upper member 2 and thence to the 110 mouth of the patient. The opening movement of the closure 5 will be determined

by the movement of the push button 12 and the closure will be instantly moved into closed position when the pressure on the push button is removed. Consequently, the amount of liquid permitted to pass through the opening 4 may be regulated at will by operation of the push button. In service, the device will be held in the position illustrated in Fig. 3 so that the liquid from the tumbler will flow along the inner wall of the upper member to the mouth of the patient and it is therefore not likely that any of the liquid will be spilled.

The device can be used without discomfort or inconvenience to the patient, and provides a simple, inexpensive device that is capable of being satisfactorily used for the purpose intended.

Obviously, I may provide many forms and modifications of the device illustrated without departing from the spirit and scope of my invention as set forth in the foregoing disclosure and outlined more particularly in the appended claims. I therefore consider such modifications and adaptations as my own.

I may provide a packing or gasket 14 of any suitable material, such as rubber, secured to the under surface of the closure 5 in any suitable manner, as by means of a screw 15, to insure a liquid tight fit between the closure and its seat.

I claim:

1. A device of the character described comprising a tumbler, a member adapted to fit tightly over the open upper end of the tumbler and to extend thereabove, said member having a transverse partition abutting the upper end of said tumbler so as to pro-

vide a closure therefor, said partition being 40 formed with an opening therethrough, and means carried by said member for controlling the flow of the liquid from said tumbler through said opening in the partition.

2. A device of the character described 45 comprising a tumbler, a member adapted to fit tightly at one end thereof over the open upper end of the tumbler, said member having a transverse partition abutting the upper end of the tumbler so as to provide a 50 closure for the same, said partition being formed with an opening therethrough, a closure for said opening, spring means for normally maintaining said closure in closed position, and means extending exteriorly 55 of the wall of said member and operable at will for opening the second named closure.

3. A device of the character described comprising a tumbler, a member adapted to fit tightly at one end thereof over the open 60 upper end of the tumbler, said member having a transverse partition abutting the upper end of the tumbler so as to provide a closure for the same, said partition being formed with an opening therethrough, a closure 65 for said opening, said closure being hinged to the partition, an arm rigidly secured to said second named closure for rocking the latter about its hinge, spring means engaging the arm for yieldingly maintaining the second named closure in closed position, a push button disposed in an opening through the wall of said member, and a lever and link mechanism connecting said push button and said arm so that the second named closure can be operated by operating the push button.

RAY JENNINGS.
